US00D678064S

(12) **United States Design Patent**
Arminak

(10) **Patent No.:** US D678,064 S
(45) **Date of Patent:** ** Mar. 19, 2013

(54) **PUMP ACTUATOR**

(75) Inventor: **Armin Arminak**, Azusa, CA (US)

(73) Assignee: **Arminak & Associates, LLC**, Azusa, CA (US)

(**) Term: **14 Years**

(21) Appl. No.: **29/413,133**

(22) Filed: **Feb. 10, 2012**

(51) **LOC (9) Cl. 09-07**

(52) **U.S. Cl. D9/448**

(58) **Field of Classification Search** D9/44, D9/445, 448, 454, 682, 686; D6/542, 544; D28/76; D23/238, 252, 255; 222/401, 402.13, 222/402.22, 566, 631

(57) **CLAIM**

The ornamental design for a pump actuator, as shown and described.

DESCRIPTION

FIG. 1 is a perspective view of the pump actuator.

FIG. 2 is a front view of the pump actuator.

FIG. 3 is a rear view of the pump actuator.

FIG. 4 is a right side view of the pump actuator.

FIG. 5 is a left side view of the pump actuator.

FIG. 6 is a top view of the pump actuator; and,

FIG. 7 is a bottom view of the pump actuator.

The portions of the pump actuator shown in broken lines form no part of the claimed design.
